REAMER CUTTER MOUNTING

John H. Howard and Philip C. Efromson, Whitier, Calif.; said Efromson assignor to Globe Oil Tools Company, Los Nietos, Calif., a corporation of California

Application June 15, 1937, Serial No. 148,297

10 Claims. (Cl. 255—73)

This invention relates to well drilling tools and relates more particularly to mountings for the cutters of well reamers. A general object of the invention is to provide practical, dependable and effective anti-friction mountings for the roller cutters of well reamers.

Another object of this invention is to provide a mounting for a roller cutter of a well reamer in which the end thrusts in both directions on the cutter are transmitted by anti-friction bearing elements.

Another object of this invention is to provide a cutter mounting of the character mentioned in which the radial thrusts on the cutter are taken 15 or transmitted by anti-friction rollers and the end thrusts are transmitted by balls, the rollers providing the required support throughout substantial portions of the length of the cutter and the balls transmitting the end thrusts with a 20 minimum of friction.

Another object of this invention is to provide a cutter mounting of the character mentioned in which a single row or series of balls assumes the end thrusts in both directions, thus greatly simplifying the construction and leaving ample space 25 for long rollers which assume the radial thrusts.

Another object of the invention is to provide a cutter mounting of the character mentioned embodying novel and very effective means for supporting the cutter bearing on the body or shank 30 of the tool.

Another object of this invention is to provide a cutter mounting of the character mentioned in which the means for mounting the cutter bearing 35 on the tool shank is such that the cutter with its bearing may be mounted on the shank and removed therefrom as a unit.

A further object of this invention is to provide a cutter mounting means of the character mentioned in which the bearing and the cutter may 40 be assembled at the place of manufacture and shipped and handled as a unit without danger of loss or displacement of any of the parts.

The various objects and features of our invention 45 will be fully understood from the following detailed description of typical preferred forms and applications of the invention, throughout which description reference is made to the accompanying drawings, in which:

50 Fig. 1 is a side elevation of a reamer embodying one form of the invention. Fig. 2 is an enlarged vertical fragmentary detailed sectional view of the reamer illustrated in Fig. 1 showing one of the cutters and its mounting means. Fig. 3 is an 55 enlarged fragmentary vertical detailed sectional

view illustrating one of the supporting pins and the adjacent parts. Fig. 4 is a view similar to Fig. 2 illustrating a modified form of the invention and Fig. 5 is an enlarged fragmentary elevation view of a block and a wedge of the structure illustrated in Fig. 4.

The cutter mounting of the present invention may be employed to rotatably support the cutters of well tools of various characters. In the following detailed description we will describe two 10 typical forms of the invention employed to rotatably support the roller cutters of a well reamer. It is to be understood that the invention is not to be construed as limited or restricted to the specific forms or applications of the invention 15 about to be described but is to be taken as including any features or modifications that may fall within the scope of the claims.

A well reamer illustrated in the drawings includes a body or shank 10 having a socket 11 in 20 one end and a threaded pin 12 on its other end for facilitating its connection in the well drilling string. The shank 10 is provided with an enlarged intermediate portion 13 of substantially triangular horizontal cross section. Vertical or 25 longitudinally extending pockets 14 are provided in the apices of the triangular portion 13. The pockets 14 are provided to receive the reaming cutters and their upper and lower walls 15 are preferably flat and substantially horizontal. A 30 central longitudinal fluid passage 16 extends through the shank 10 from one end to the other to conduct the circulation fluid.

A reaming cutter 17 is provided in each pocket 14. The cutters 17 are generally cylindrical and 35 are of substantial length. Central longitudinal openings 18 extend through the cutters 17 and the upper and lower ends 19 of the cutters are preferably flat. The cutter openings 18 may be of uniform diameter with the exception of a 40 single race in each cutter opening, as will be hereinafter described. The lower portions of the cutters 17 are tapered and suitable axially extending cutting teeth 20 are provided on the cutters to act on the earth formation at the side 45 wall of the well bore. The means or mountings for mounting the several cutters 17 may be identical. We will proceed with a detailed description of the mounting for one of the cutters 17, it being understood that this description is 50 equally applicable to the mountings of the other cutters.

The improved cutter mounting of the present invention comprises, generally, detachably connected shaft members or bearing members 21 ex- 55

tending through the opening 18 of the cutter 17, sets of rollers 22 cooperating with the members 21 and the wall of the cutter opening 18 to support the cutter against radial thrusts, a set of 5 balls 23 cooperating with the members 21 and the cutter 17 to support the cutter against end thrusts and means 24 cooperating with the members 21 to support the same where the cutter 17 is rotatable in a pocket 14.

10 The shaft members or bearing members 21 are adapted to be connected to constitute the cutter supporting pin or shaft. The members 21 are elongate substantially cylindrical members and are alike or complementary. There are two members 15 21 of substantially the same diameter and the members are receivable in the cutter opening 18 with suitable clearance. The adjacent inner ends of the two members 21 are releasably or detachably connected. A socket 25 of reduced 20 diameter is provided in the inner end of one member 21 and an extension or pin 26 is provided on the inner end of the other member 21 and is threaded in the socket 25 to connect the two members. The pin 26 threaded in the socket 25 25 connects the two members 21 so that their inner ends are in abutment. The members 21 are preferably of equal length and the aggregate length of the members is equal to or slightly greater than the length of the cutter 17 so that the outer 30 ends of the members 21 are at or adjacent the ends 19 of the cutters 17. The outer ends of the bearing members 21 may be flat.

The sets of rollers 22 are arranged between or cooperate with the members 21 and the wall of 35 the cutter opening 18 to transmit the radial thrusts between the cutter 17 and the members. In the preferred construction there are two longitudinally spaced sets of rollers 22, it being understood that there may be a greater number of sets 40 of shorter rollers provided if desired. Each bearing member 21 has an annular depression or circumferential groove 27 spaced between its ends to receive a set of rollers 22. The grooves 27 are of substantial length and the two grooves are preferably equally spaced from the central transverse axis of the cutter 17. An annular set or 45 series of rollers 22 is provided in each groove 27. The rollers 22 are of substantial length to have extensive longitudinal engagement with the wall 50 of the cutter opening 18 and the inner walls of the grooves 27. The ends of the rollers 22 may cooperate with the end walls of the grooves 27 to limit the endwise movement of the rollers. It will be understood how the longitudinally spaced sets 55 of rollers 27 effectively and dependably transmit the radial operating thrust between the cutter 17 and the bearing members 21.

The row or set of balls 23 is provided to transmit the end thrust between the cutter 17 and the 60 bearing members 21. It is a feature of the invention that there may be a single circumferential row or series of balls 23. The row of balls 23 is spaced substantially midway between the opposite ends 19 of the cutter 17. An annular race or 65 groove 28 of partially cylindrical cross section is provided in the wall of the cutter opening 18 midway between the ends of the cutter 17 to cooperate with or partially receive the balls 23. An annular groove 29 of partially cylindrical cross 70 section is formed in the assembly of the two members 21 to directly oppose the groove 28. In practice the groove 29 has substantially equal portions in the abutting inner ends or corners of the members 21. The grooves 28 and 29 may 75 both be of substantial depth so that the two

grooves are adapted to substantially entirely receive the balls 23. It will be apparent how the balls 23 cooperating with the grooves 28 and 29 effectively transmit the end thrusts in both directions between the cutter 17 and the members 21 with a minimum of friction. It is important to note that only a single set of balls 23 is required for the transmission of the operating end thrusts in both directions. Further, it will be observed that the balls 23 cooperating with the grooves 28 and 29 prevent longitudinal separation or displacement of the cutter 17 from the bearing members 21 when the assembly of the cutter and its bearing parts is separate or detached from the reamer.

The means 24 for supporting or mounting the 15 bearing members 21 supports the same on the shank 10 where the cutter 17 is in its proper operative position in a pocket 14. The means 24 is characterized by its simplicity and dependability. In the form of the invention illustrated in Figs. 20 1 to 3, inclusive, of the drawings, the means 24 includes screws 30 threaded in vertical or longitudinal openings 31 in the shank portion 13. The openings 31 extend from the ends of the shank portion 13 to the upper and lower walls 15 of the 25 pocket 14 and the openings are in vertical or longitudinal alignment. The screws 30 are threaded in the openings 31 to have portions project into the pockets 14 to cooperate with the bearing members 21. In the particular construction illustrated in the drawings the screws 30 and the openings 31 have self-locking threads 32 of the "Dardelet" type whereby the screws are locked against loss or loosening when sufficient stress is placed on them, as will be hereinafter described. It is to be understood that the screws 30 may be locked in place by other suitable means, if desired. Reduced polygonal heads 33 may be provided on the outer ends of the screws 30 to facilitate their turning or threading with a suitable wrench. The heads 33 are preferably entirely within the openings 31.

The means 24 further includes cooperating tapered plug parts and sockets on the screws 30 and members 21 whereby the screws 30 support the members 21 and hold the members against movement and turning. In the construction illustrated in the drawings a tapered plug part 35 is provided on the inner end of each screw 30. The plug parts 35 are integral with the screws 30 and are preferably frusto-conical, having flat inner ends. The outer ends of the bearing members 21 have central tapered sockets 36 for receiving the plug parts 35. The cooperation of the plug parts 35 with the sockets 36 definitely locates the bearing members 21 and prevents shifting and turning of the members whereby the cutter 17 is dependably supported on the shank 10. Polygonal sockets 37 may continue inwardly from the inner ends of the sockets 36 to receive wrenches 60 for threading the members 21 together and for disconnecting the members. The pitch of the surfaces of the plug parts 35 and the walls of the sockets 36 is such that the cooperation of the parts with the sockets securely holds the members 65 21 against shifting and against rotation. With the plug parts 35 in cooperation with the sockets 36 the members 21 are supported where their ends 19 are clear of the end walls 15 of the pocket 14 and the ends 19 of the cutter 17 have suitable 70 clearance with the end walls of the pockets.

In assembling a cutter 17 on the shank 10 a set of rollers 22 is first assembled in the groove 27 of one of the members 21 and the member carrying its rollers is then inserted in the cut- 75

- ter opening 18. The balls 23 are then dropped in the open end of the opening 18 and when a sufficient number of balls has been dropped in, the member 21 is moved to a position where the balls are received in the groove or race 28. The rollers 22 are then arranged in the groove 27 of the other bearing member 21 and the said other bearing member 21 with its rollers is inserted in the cutter opening 18. The two members 21 are then threaded together. This threading together of the members 21 brings their inner ends into abutment and completes the race or groove 29, which cooperates with the balls 23. The balls 23 cooperating with the grooves 28 and 29 serve to prevent relative longitudinal movement between the cutter 17 and the connected members 21 so that the several parts of the assembly are retained in their proper positions.
- 20 To mount the assembly on the shank 10 the screws 30 are backed out of the pocket 14 and the cutter 17 is arranged in its approximate position in the pocket. The screws 30 are then threaded inwardly to have their plug parts 35 cooperate with the sockets 36. The screws 30 may be threaded to positions where the cutter 17 is mounted in its proper position in the pocket 14. The tightening down of the screws 30 to force their plug parts 35 into tight engagement with the walls of the sockets 36 dependably prevents shifting of the connected members 21 and the rotation of the members 21 so that the cutter 17 is dependably mounted in the pocket 14. Tightening down of the screws 30 also causes automatic binding or locking of the self-locking threads 32.
- In the operation of the reamer the cutter 17 cooperates with the side wall of the well bore and rotates about its own axis. The rollers 22 have extensive or long engagement with the wall of the cutter opening 18 and with the walls of the grooves 27 to effectively transmit the radial thrusts between the cutter and the members 21. The balls 23 cooperating with the grooves 28 and 29 transmit the end thrusts in both directions between the cutter 17 and the members 21. The balls 23 transmit these end thrusts with a minimum of friction. It will be understood how the cutter 17 and its bearing elements may be easily removed from the shank 10 for repair and replacement by backing off the screws 30.
- Figs. 4 and 5 of the drawings illustrate a modified form of the invention in which the bearing members 21 are supported by blocks. The cutter 17, the bearing members 21, the rollers 22 and the balls 23 may be the same as in the previously described form of the invention. In the construction illustrated in Figs. 4 and 5 of the drawings the portion 13 of the shank has vertical or longitudinal grooves 40 communicating with the opposite ends of the pocket 14. A shiftable block 41 is arranged in each groove 40. The blocks 41 are shiftable vertically or longitudinally in the grooves 40 and have vertical slots 42. Screws 43 are passed through the slots 42 and are threaded into openings 53 in the shank 10. Round or cylindrical heads 44 are provided on the screws 43 and are adapted to clamp against shoulders 45 at the mouths of the slots 42. Tapered plug parts 46 are provided on the blocks 41 to cooperate with the sockets 36 in the bearing members 21. The plug parts 46 may be similar to or identical with the plug parts 35, described above.
- 75 Wedge means are provided for urging the blocks 41 toward the outer ends of the members 21 to effect the proper cooperation of the plug parts 46 with the sockets 36. A wedge 47 is arranged in the outer part of each groove 40. The wedges 47 are adapted to engage between the outer ends of the blocks 41 and the outer walls of the grooves 40. The outer ends 48 of the blocks 41 are tapered or inclined and the wedges 47 have correspondingly inclined faces cooperating with the ends 48. Screws 49 are passed inwardly through openings 50 in the wedges 47 and are threaded into openings 51 in the shank 10. The heads of the screws 49 are preferably received in the outer portions of the openings 50.
- When the assembly of a cutter 17 and its bearing elements is to be mounted in the pocket 14 the blocks 41 may be moved to retracted positions so that their plug parts 46 are clear of the pocket. The assembly of the cutter and its bearing elements is arranged in place in the pocket 14 and the blocks 41 are moved to positions where their plug parts 46 are received in the sockets 36. The screws 43 are threaded in the openings 53 and left in a loosened condition to allow shifting of the blocks 41. The wedges 47 are then entered in the outer portions of the grooves 40 and the screws 49 are tightened down. Tightening down of the screws 49 brings the wedges 47 into wedging cooperation with the inclined ends 48 of the blocks 41 and the wedges urge the blocks inwardly toward the ends of the cutter 17 so that the plug parts 46 are tightly forced into the sockets 36. The screws 43 are then tightened down. The plug parts 46 cooperating with the sockets 36 dependably hold the bearing members 21 in position and prevent rotation of the bearing members.
- Having described only typical preferred forms and applications of our invention, we do not wish to be limited or restricted to the specific details herein set forth, but wish to reserve to ourselves any variations or modifications that may appear to those skilled in the art or fall within the scope of the following claims.
- Having described our invention, we claim:
1. A well reamer comprising an elongate shank, an elongate roller cutter having a longitudinal opening, a supporting element extending through the opening from one end of the cutter to the other, means engaging the opposite ends of the element and supporting the element in substantially parallel relation to the longitudinal axis of the shank, a single anti-friction bearing transmitting end thrusts in both directions from the cutter to the element, and bearing means transmitting the radial thrusts from the cutter to the element.
  2. A well reamer including a shank, an elongate roller cutter having a longitudinal opening, a supporting element extending through the opening from one end to the other, means engaging the opposite ends of the element and removably supporting the element in a substantially vertical position on the shank, a single anti-friction bearing cooperating with the element and the interior of the cutter substantially midway between the ends of the cutter and transmitting end thrusts in both directions from the cutter to the element, and bearing means transmitting the radial thrusts from the cutter to the element.
  3. A well reamer including a shank, an elongate roller cutter having a longitudinal opening, a supporting element extending through the opening from one end to the other, means en-

gaging the opposite ends of the element and removably supporting the element in a substantially vertical position on the shank, a single row of balls transmitting end thrusts in both directions from the cutter to the element, and bearing means transmitting the radial thrusts from the cutter to the element.

4. A well reamer comprising a shank, an elongate roller cutter having an opening, a supporting element extending through the opening from one end of the cutter to the other, means removably supporting the ends of the element on the shank, the wall of the opening and the element having a pair of opposing ball races, balls in the races transmitting end thrusts in both directions between the cutter and the element, and sets of rollers at opposite sides of the races cooperating with the wall of the opening and the element and transmitting radial thrusts between the cutter and element.

5. A well reamer comprising a shank, a roller cutter having an opening, a supporting element extending through the opening from one end to the other, means removably supporting the opposite ends of the element on the shank so that the element is substantially parallel with the longitudinal axis of the shank, the wall of the opening and the element having a pair of opposing ball races substantially midway between the ends of the cutter, balls in the recess transmitting end thrusts in both directions between the cutter and the element, and sets of rollers at opposite sides of the races cooperating with the wall of the opening and the element and transmitting radial thrusts between the cutter and element.

6. A well reamer comprising, a shank, a roller cutter having a longitudinal opening, two threadedly connected members in the opening, a single row of balls cooperating with the interior of the cutter and the connected members transmitting end thrusts in both directions between the cutter and the members, rollers cooperating with the interior of the cutter and the members transmitting the radial thrusts between the cutter and the members, and means mounting the ends of the assembly of the members on the shank.

7. A well reamer comprising, a shank, a roller cutter having a longitudinal opening, there being a ball race in the wall of the opening between the ends of the cutter, two shaft members, one entering each end of the opening, means threadedly connecting the inner ends of the members, there being grooves in the inner por-

tions of the members joining to form a ball race which opposes the first mentioned race, a series of balls in the races transmitting end thrusts in both directions between the cutter and the members, and means supporting the outer ends of the members on the shank.

8. A well reamer comprising, a shank, a roller cutter having a longitudinal opening, there being a ball race in the wall of the opening between the ends of the cutter, two shaft members, one entering each end of the opening, means threadedly connecting the inner ends of the members, there being grooves in the inner portions of the members joining to form a ball race which opposes the first mentioned race, a series of balls in the races transmitting end thrusts in both directions between the cutter and the members, each member having a groove, rollers in grooves cooperating with the wall of the opening and transmitting the radial thrusts between the cutters and the members, and means supporting the outer ends of the members on the shank.

9. A well reamer comprising a shank having a pocket, a roller cutter having a longitudinal opening, and means for rotatably supporting the cutter in the pocket including two elements, one a cutter support extending through the opening, the other a member shiftably secured to the shank, there being a tapered socket in one element, a plug part on the other element cooperating with the socket, and means for shifting the said member on the shank to effect engagement and disengagement of the plug part and socket, the last mentioned means including a wedge cooperable with the said member, and a screw for setting the member in adjusted position.

10. A well reamer comprising a shank having a pocket, a roller cutter having a longitudinal opening, and means for rotatably supporting the cutter in the pocket including two elements, one a cutter support extending through the opening, the other a member shiftably secured to the shank, there being a tapered socket in one element, a plug part on the other element cooperating with the socket, and means for shifting the said member on the shank to effect engagement and disengagement of the plug part and socket, the last mentioned means including a wedge cooperable with said member.

JOHN H. HOWARD.
PHILIP C. EFROMSON.
